UNITED STATES PATENT OFFICE

127,290

DESIGN FOR AN ALPHABET FOR FORMING MONOGRAMS OR SIMILAR ARTICLE

George A. Armstrong, Edgewood, R. I., assignor to
William C. Greene Company, a corporation of
Rhode Island

Application March 3, 1941, Serial No. 99,294

Term of patent 7 years

To all whom it may concern:

Be it known that I, George A. Armstrong, a citizen of the United States of America, residing at Edgewood, county of Providence, State of Rhode Island, have invented a new, original, and ornamental Design for an Alphabet for Forming Monograms or Similar Article, of which the following is a specification, reference being had to the accompanying drawing, forming a part thereof.

Fig. 1 is a face view of the letters of the alphabet showing my design; and Figs. 2 and 3 are, respectively, sectional views on lines 2—2 and 3—3 of the letter "A", showing a feature typical of the other letters of the alphabet.

I claim:

The ornamental design for an alphabet for forming monograms or similar article, substantially as shown and described.

GEORGE A. ARMSTRONG.
